LEROY G. W. FELDERMANN, OF GALENA, ILLINOIS

TRACTOR CONTROL

Application filed May 3, 1928. Serial No. 274,926.

The present invention relates to an improved device which may be conveniently referred to as a tractor control, the same being especially, but not necessarily adapted for use 5 upon a tractor of the McCormick Deering type.

From experience I have found that it is frequently difficult for a single person to operate a tractor and farm appliance, which 10 is coupled thereto, under certain conditions. For example, when traveling over unusually rough ground or passing over a ditch or the like, the operator must have at his command both hands for safe operation of the plow 15 as well as the tractor.

This makes it substantially impossible to actuate the carburetor throttle at this time, and requires the operator to place his foot on the clutch and to throw it out of operation 20 momentarily. Hence, even though the clutch is thrown out, the engine runs "wild" for the time being, frequently resulting in burning out of the bearings.

Having observed this from time to time I 25 have discovered the need for a device which will permit the engine to be throttled down at this time, without throwing out the clutch, and by using the foot to actuate the improved control device, whereby to allow the operator 30 the freedom of use of both hands to carry out other necessary operations at this otherwise disastrous moment.

The invention, previously stated, comprises a foot control actuating device for 35 cutting down the speed of the engine by operating the carburetor throttle and temporarily throwing out of operation the governor. The invention is however not to be confused with a foot accelerator because it operates in a substantially reverse manner.

The particular details and their relative arrangement in association, and method of application will become more readily apparent 40 from the following description and drawings.

In the drawings:—

Figure 1 is a perspective view of a portion of a conventional type of tractor showing the improved foot controlled device associated therewith.

Figure 2 is an enlarged perspective view of certain of the details.

Referring now to the drawings by numerals it will be observed that the reference character 3 designates the customary transmission, 4 the engine, 5 the carburetor, 6 the governor, 7 the hand operated throttle controlled rod. These are ordinary details and are merely shown and referred to for purpose of illustration of the manner of use.

In carrying out the invention I provide a longitudinally movable foot controlled rod 8. The rear end of this rod is formed to provide a suitable foot pedal 9 and at this point it extends through appropriate guide 60 brackets 10.

It also extends through additional guide brackets 11 on the frame, and at this point it is provided with adjustable stops 12. The forward portion embodies an offset portion 70 13 with which a return spring 14 is connected.

The forward end of the right angular part 13 connects with one of the arms of a bell crank 15 pivotally mounted on supporting 75 bracket 16 attached either to the engine or the governor as shown. Connected with the other arm of the bell crank is a link 17 which is in turn connected with a throttle valve shaft 18 leading to and operatively connected with a throttle valve of the carburetor 5. In this connection I might state that the aforesaid hand controlled rod 7 is provided 80 with a depending link 19 having an elongated loop 20 operatively connected with the shaft 18. I would also call attention to additional link 21 connected with the shaft 18 and operatively connected with the governor 6.

As before pointed out, it is difficult for one 90 man to properly manipulate a tractor and plow or a similar appliance under certain working conditions. For example, when a ditch is approached and careful driving is necessary, both hands are occupied, one to 95 steer the tractor and the other one to regulate the plow, thereby not allowing use of the hand throttle. Hence, there is no way to slow down the tractor but to slip the clutch out. With this foot controlled contrivance how- 100

ever, it is easy to do this without throwing out the clutch but by simply placing the foot on the pedal and pushing forwardly on the operating rod. Hence through the medium of the complementary mechanism, the carburetor is throttled down and the governor temporarily thrown out of use.

The device is characterized by exceptional simplicity and durability, and is capable of fulfilling the requirements of a structure of this class in a dependable and efficient manner.

These and other advantages and features have doubtless been made apparent from the foregoing description and drawings. Consequently, a more lengthy description is regarded unnecessary.

Minor changes in size, shape and rearrangement of parts coming within the field of invention claimed may be resorted to if desired.

Having thus described the invention, what I claim as new is:—

A structure of the class described comprising in combination, a tractor embodying an engine, a carburetor, a governor, and a throttle shaft connected with the carburetor, a hand actuated throttle control device associated with said shaft; a foot actuated rod, said foot actuated rod at one end being formed to provide a substantially U-shaped extension extending laterally from said foot actuated rod, and constituting a foot pedal for the rod, brackets mounted on the frame of the tractor for slidably supporting said foot actuated rod, and an adjustable stop member carried by the last mentioned rod intermediate said bracket for engagement with one of the brackets for limiting the sliding movement of said rod in one direction, said rod adjacent its opposite end being offset, a return spring secured to one of said brackets and the offset end of said foot actuated rod, a bellcrank, a support for said bellcrank, a link connection between said throttle shaft and one arm of said bellcrank, a link connection between said throttle valve shaft and said governor, and the offset end of said foot actuated rod adapted to be connected to the other arm of said bellcrank lever, as and for the purpose specified.

In testimony whereof I affix my signature.
LEROY G. W. FELDERMANN.
